William Gorman

United States Patent Office.

WILLIAM GORMAN, OF NEW BRITAIN, CONNECTICUT, ASSIGNOR TO RUSSELL & ERWIN MANUFACTURING COMPANY, OF SAME PLACE.

Design No. 3,915, dated March 22, 1870.

DESIGN FOR DRAWER-PULL.

The Schedule referred to in these Letters Patent and making part of the same.

To all whom it may concern:

Be it known that I, WILLIAM GORMAN, of New Britain, in the county of Hartford and State of Connecticut, have originated and designed a new Design for a Drawer Pull; and I do hereby declare that the following is a full, clear, and exact description thereof, taken in connection with the drawings making a part of this specification.

That portion of the pull which is parallel with the face of the drawer is designated by the parallel band-lines *a a* in relief, extending around the angular turn at the corners, and intersecting with the ear-pieces *b*, which contain the screw-holes. The space between the lines is filled with a cordon of rosettes, *c*, upon a plain or matted ground.

The shed-roof or finger-guard portion of the pawl has an edge band-line, *d*, in relief, intersecting with supporting-scrolls *e* at the corners. The space forming the surface of the finger-guard is occupied by scrolls, rosettes, and leaf-work in relief, upon a matted ground, as shown.

What I claim as my invention, and desire to secure by Letters Patent, is—

The design for a drawer-pull, substantially as shown and described.

WILLIAM GORMAN.
